UNITED STATES PATENT OFFICE.

DANIEL HANLON, OF SPOKANE, WASHINGTON.

BOILER.

940,684.

Specification of Letters Patent. Patented Nov. 23, 1909.

Application filed May 17, 1909. Serial No. 496,353.

To all whom it may concern:

Be it known that I, DANIEL HANLON, a citizen of the United States, residing at Spokane, in the county of Spokane and 5 State of Washington, have invented new and useful Improvements in Boilers, of which the following is a specification.

My present invention has relation to boilers, such as are designed more especially for 10 use in hot water heating systems, and its novelty, utility and practical advantages will be fully understood from the following description and claim when the same are read in connection with the drawings accompanying and forming part of this specification, in which:

Figure 1 is a view partly in side elevation and partly in longitudinal vertical section of a boiler constructed in accordance with 20 my present invention. Fig. 2 is a front elevation of the boiler as the same appears with the smoke-uptake removed. Fig. 3 is a detail transverse section taken in the plane indicated by the line 3—3 of Fig. 1 and showing 25 the arrangement of the depending side portions of the upper water container in the recesses in the side walls or portions of the lower water container.

Similar letters designate corresponding 30 parts in all of the views of the drawings, referring to which:

A is the base or foundation of my novel boiler, which is, by preference, formed partly of brick, as indicated by *a*, and partly 35 of cast-metal, as indicated by *b*. The cast-metal portion *b* forms an ash pit *c*, and in its forward wall is provided with an opening designed to be closed by a door *d* of conventional or any other suitable construction.

Arranged above the ash pit *c* and supported by the metallic base portion *b* is a suitable grate *e*, and also supported by the metallic base portion is a bridge wall *f*, which, in the preferred embodiment of my 45 invention, is adjustable in the direction of the length of the apparatus to meet the requirements of different fuels.

Superposed on the metallic base portion *b* is a front water containing section *C*, of 50 cast-metal, preferably shaped as best shown in Fig. 2, and having door openings *g* and *h*. From the upper portion of the said section *C* extends a pipe *D* adapted to be connected with the pipes forming a hot water heating 55 system (not shown).

E E are hollow side sections, of cast-

metal, which are superposed on the base *A* and abut at their forward ends against the inner side of the section *C* to the interior of which their interiors are connected, preferably through the medium of heavy slip nipples *F*, such as shown by dotted lines in Figs. 1 and 2. The section *C* may be connected to and held tight against the side sections *E* in any manner consonant with the purpose of my invention, though I prefer to effect the connection through the medium of suitable bolts *i* secured in lugs *j* on the sections. The upper sides or edges of the side sections *E* are concave, as indicated by *k*, 70 and in the preferred embodiment of my invention the outer walls are tapped, as indicated by *l*, for the connection of pipe sections hereinafter described.

Superposed on the rear of the brick portion *a* of base *A* is a water containing section *G*, which is preferably of cast-metal and concavo-convex in cross-section, its concave side being inward or adjacent to the rear ends of the side sections *E* as shown in Fig. 1. The said section *G* is connected through pipes *H* with the taps *l* of the side sections *E*, and connected to the upper portion of the said section *G* is a pipe *L* designed to lead water from the circulating pipes of the heating system back to the boiler. From this it will be manifest that when the water in the circulating system has given off its heat, it will pass through pipe *L* to the rear cast-metal section *G*, and from the lower portion of the latter will pass through pipes *H* to the lower and rear portions of the side sections *E* and from the latter will pass through the nipples *F* into the front section *C*. At this time the water will be heated to a considerable extent because of its passage through the highly heated sections and in close proximity to the fire, and from the upper portion of the section *C* the heated water will pass through the pipe *D* back to the pipes of the circulating system.

It will be readily gathered from the foregoing that the sections *C*, *E* and *G* may be readily set upon the base *A* and as readily connected together; the lower portion of the rear section *G* being connected with the rear ends of the sections *E* through the medium of lugs and bolts such as *i* and *j*, or other suitable means.

I is the shell of the upper water container comprised in my novel boiler. The said shell is concave in cross-section at its

under side, is connected with the rear cast-metal section G through the medium of a hook p and an eye-bolt r, Fig. 1, and has depending side portions s seated in the 5 cavities k in the upper sides of the side sections E. Extending through the shell I which is provided with an inlet t for water and an outlet u for steam, are flues J, suitably fixed to the heads of the shell and de- 10 signed to carry the products of combustion through the same. From the forward ends of the flues J the smoke and other products of combustion pass into an uptake K which is connected to the shell I and to the front 15 cast-metal section K in the manner illustrated, or in any other manner compatible with the purposes of my invention.

When desirable the front wall of the uptake K may be comprised in a cast-iron 20 frame which I contemplate employing in front of the cast-metal section C to carry the doors complementary to the openings g and h in the said frame. I would also have it understood that when deemed expedient the 25 said frame may be equipped with doors positioned to afford ready access to the flues for cleaning purposes, but inasmuch as the said cast-iron frame is well known and does not form part of my present invention, I 30 have deemed it unnecessary to illustrate the same.

By reason of the water-containing shell I being concave in cross-section at its under side, the flames and other products of combustion are deflected downwardly and outwardly to the inner sides of the water-containing side sections E, and in that way the 35 said side sections are adequately heated. It will also be observed in this connection that 40 the transverse concavity in the under side of the shell I provides the said shell with depending side portions, and that said depending side portions serve by resting in the 45 seats or concavities k in the upper edges of the side sections E to strongly hold the shell I and sections E together.

In the practical operation of my improvements, the products of combustion from the fire on the grate e pass rearwardly between 50 the hollow side sections E and thence upwardly in front of the hollow rear section G, and during such passage raise the temperature of the water contained in the said section. It will also be noticed at this point 55 that the fire on the grate e will, because of its being in close proximity to the section C, highly heat said section and the water contained therein so that the water will be heated to a high degree immediately prece-

dent to its passage back to the pipes of the 60 circulating system. It will also be noticed that the products of combustion after passing upwardly at the inner side of the section G will pass forwardly through the flues J to the uptake, and thence out of the apparatus. 65

By virtue of the arrangement described it will be manifest that steam will be generated in the steel shell I, and that the said steam may be put to any use desired. 70

It will be gathered from the foregoing that in addition to the facility with which my novel boiler may be installed, the said boiler is advantageous in that it is simple and inexpensive in construction and is well 75 adapted to withstand the usage to which boilers are ordinarily subjected.

The construction herein illustrated and described constitutes the best practical embodiment of my invention that I have as 80 yet devised, but it is obvious that in the future practice of the invention such changes or modifications may be made as do not involve departure from the scope of my invention as defined in the claim appended. 85

Having described my invention, what I claim and desire to secure by Letters-Patent, is:

A boiler comprising a suitable base, a water-containing shell disposed above the 90 base and having an under side concave in cross-section and also having longitudinal hollow depending portions at opposite sides of said concave underside, longitudinal flues extending through said shell, a front hollow 95 water-containing section superposed on the base and arranged in front of the shell, a rear hollow water-containing section, superposed on the base and having a concave inner side opposed to the rear end of the 100 shell, side hollow water-containing sections superposed on the base and interposed between and connected with the front and rear sections and having crosswise concavities in their upper sides receiving and holding the 105 depending side portions of the shell, and an uptake arranged above the front water-containing section and adapted to receive products of combustion from the forward ends of the flues in the shell. 110

In testimony whereof I have hereunto set my hand in presence of two subscribing witnesses.

DANIEL HANLON.
